ARTICULATED OVERHEAD DOOR

David M. Robinson, New Britain, Conn., assignor
to The Stanley Works, New Britain, Conn., a
corporation of Connecticut

Application April 30, 1934, Serial No. 723,015

12 Claims. (Cl. 20—20)

This invention relates to improvements in builders' hardware, such as is applicable for supporting vertically movable or overhead doors, and has for one of its objects the provision of improved hardware of the character described, that is easy to install and align and does not require special tools or expert workmen.

A further object lies in the provision of such improved hardware that is particularly durable in use and which renders the action of the door unusually smooth and effortless.

A still further object resides in the provision of improved hardware of the character described which renders the counterbalancing of the door particularly easy and accurate and not liable to get out of adjustment in service.

Other objects and advantages will appear as the description proceeds.

In the accompanying drawings, in which like reference numerals have been used to indicate similar parts throughout, I have illustrated a suitable mechanical embodiment of the idea of the invention. The drawings, however, are for the purpose of illustration only and are not to be taken as limiting the invention the scope of which is to be measured entirely by the scope of the appended claims.

In the drawings,
30 Fig. 1 is a vertical sectional view through a garage building showing a section of the door in closed position and the improved hardware in assembled form as applied to the building and door;

35 Fig. 2 is a plan view of a portion of the door counterbalancing means, the counterbalancing spring being shown in section;

40 Fig. 2a is a view similar to Fig. 2 showing a continuing portion of the counterbalancing means;

Fig. 3 is a sectional view taken on the line 3—3 of Fig. 2a;

45 Fig. 4 is a sectional view taken on the line 4—4 of Fig. 2;

Fig. 5 is an edge elevational view of a safety stop comprising one element of the improved hardware;

Fig. 6 is an elevational view of the safety stop illustrated in Fig. 5, a portion being broken away to better illustrate the construction thereof;

Fig. 7 is an elevational view on an enlarged scale of a fragmentary portion of the track and track bracket illustrated in Fig. 1 and showing the door in dotted lines in a partly raised position;

Fig. 8 is a sectional view on the line 8—8 of Fig. 7;

Fig. 9 is an end elevational view of the joint plate illustrated in Fig. 8; and

Fig. 10 is a perspective view of the joint plate 5 illustrated in Figs. 8 and 9 in disassociated relation.

Referring to the drawings in detail, the numeral 10 generally indicates the structure of a garage building provided with side walls and a front wall and with a door opening 12 in said front wall closed by a door 15. The door 15, as illustrated, is of the type known to the art as an articulated overhead door, and is opened by moving the same from the vertical position illustrated in Fig. 1 to a horizontal overhead position within the garage building. The door is closed by moving it from the horizontal position to the vertical position. In order to support the door and guide the same from one to the other of its two operative positions, I have provided a track, generally indicated at 17, having a vertical portion 18, a horizontal portion 19, and a partly circular or fillet portion 20 joining the adjacent ends of the vertical and horizontal portions.

It is, of course, understood that similar tracks are positioned at each side of the door opening to engage the opposite edges of the door. However, as these tracks are similar in all respects, except that one may be considered as right-hand and the other as left-hand, it is believed that a description of only one of them is sufficient for the purpose of this disclosure. This track has a cross section, as particularly illustrated in Fig. 8, substantially channel-shaped except that one 30 leg of the channel is bent inwardly at the extremity thereof to form a roller channel 22. The vertical portions of the track intermediate their ends are secured to the garage building by means of track brackets 23, and the upper end of each 40 vertical portion 18 and the adjoining end of the corresponding curved portion 20 of the track are secured together and secured to the building by a joint plate, particularly illustrated in Figs. 8, 9, and 10.

In order to easily and permanently secure the abutting ends of the vertical and curved portions of the track together in alignment with each other and to the garage building, I provide a relatively wide plate 24 having a flange 25 along one 50 edge thereof. This flange is apertured, as indicated at 26, and screws 27 extend through these apertures into the door jamb to secure the plate to the building. The upper end of the vertical portion 18 of the track 17 is secured to the lower 55

part of one face of this plate 24 by suitable means, such as welding or riveting, and a spacer member 28 is interposed between the adjacent surfaces of the plate and track member to maintain the track member offset from the plate by the thickness of the spacer member. I have also provided a hook plate 29 rigidly secured to the side of the curved portion 20 of the track adjacent to the lower end thereof. This hook plate 10 is of the same thickness as the spacer member 28 and has its end portion, adjacent the outer vertical edge of the plate 24, bent over to form a hook 30 adapted to engage the edge of the plate 24 to bring the abutting ends of the track portions 18 and 20 into exact alignment with each other. The plate 24 and the hook plate 29 are provided with registering apertures 31 and 32 through which a bolt 33 extends to secure the hook plate to the support plate 24 in assembled 15 relation.

The partly circular portion 20 of each track member is welded or otherwise suitably secured to a substantially triangular flanged plate 35, the flange 36 of which is apertured for the passage therethrough of screws 30' for rigidly securing the plate to the garage building. For the purposes of swinging the upper panel of the door away from the door frame upon initial opening movement of the door, and camming the upper 30 panel against the door frame or jamb as the door is brought to final closed position, there are provided, at opposite sides of the door opening and above the curved portions of the tracks, short track or cam members 37. Each short track or 35 cam member 37 is materially narrower than the main track member 17 and is secured to the plate 35 in such manner that it is tangent to the outside of the curved portion 20 of the main track at substantially the center thereof. Each member 40 37 is a channel member and, as particularly illustrated in Fig. 7, the flanges, at the lower ends thereof, extend beyond the web and are curved and extended downwardly, as indicated at 38 and 39, the downwardly extending portion of the 45 flange 39 having a straight portion 39a inclined toward the door jamb in such a manner as to form a cam cooperating with a stud 40 secured to the upper corner of the door, to urge the top of the door firmly against the jamb when the door is in its lowermost position, and a bent over end portion 39b adapted to rest on the upper surface of the main track portion 20 to provide an abutment to brace the inclined or cam portion 39a. The lower end portion of the upper web 50 38 diverges from the cam portion of the web 39 to constitute a guideway for guiding the stud 40 into the track 37. At the upper end of the member 37, the lower flange is also bent downwardly until it substantially contacts the upper surface of the curved portion 20 of the main track, as indicated at 41, to guide the stud 40 into the 55 guide track 37 when the door is moved from its open to its closed position.

In the form of the invention herein illustrated, I have disclosed an articulated door made up of four horizontal sections hinged together along their abutting edges. As indicated in Fig. 1, each of the hinges comprises overlapping members 42 and 43 secured respectively to adjoining sections of the door and hingedly connected together by 60 means of a pintle 44. Each of the pintles 44 carries at its outer end an antifriction roller 45 adapted to run in the track 17 and to guide and support the door in its movements from one to the other of its two operative positions. In addition to the rollers 45 secured to the hinge pins

44, I have provided at the upper end of the door an additional roller 45' secured to the door by means of an upwardly projecting, hinged radius arm 48, secured to the inner surface of the door adjacent to the edge thereof by means of a suitable hinge connection 49. The hinged radius arms 48 are bent, as indicated at 48a, so that, when the door is in a raised or partly raised position, wherein the rollers 45 are supported on the curved or horizontal portions of the tracks, the upper section of the door will rest upon the arms 48, and the studs 40 will be carried above the curved or horizontal portions of the tracks so that these studs will readily enter the upper ends of the guide tracks 37. As explained above, the 10 construction illustrated comprises a right-hand and left-hand track, and these are illustrated at 15 17 and 17' in Fig. 2. The track 17' is provided with a curved portion 20' and a plate 35' similar to the plate 35.

Upon the upper portion of the plate 35, I have secured, by suitable means, such as the bolts 51, an additional plate 53, and upon the plate 35' I have secured a similar additional plate 53'. These plates 53 and 53' are apertured, as indicated at 25 54 in Fig. 2, and serve as bearing brackets to support roller bearings 55 and 55'. A shaft 60, located parallel to the top of the door opening and somewhat above and back of the same, projects through the two roller bearings 55 and 55', and 30 is rotatably supported therein. This shaft 60 is preferably hexagonal in shape and may be formed from a section of cold rolled, hexagonal stock of the proper length and diameter.

Between the plates 35 and 35', the shaft 60 35 is surrounded by a coiled spring 70 wound upon the shaft so that the tension thereof counterbalances the weight of the door during the opening and closing movements of the door, and between this spring and the shaft, I have provided a skeleton spring arbor, generally indicated at 72. The spring arbor illustrated comprises three sections, two end sections 72a and 72c, and a center section 72b. Each section of the 40 spring arbor comprises, in general, a series of 45 channel-shaped, longitudinally extending members equally spaced about the circumference of the shaft and supported by spaced cup-shaped supporting members, the longitudinally extending members of the several sections being respectively indicated by the characters 73a, 73b, and 73c, and the cup members by the characters 74a, 74b, and 74c. The end section 72a has two cup members 74a to which the rods or members 73a are secured, one of these cup members 55 being at the extreme end of the arbor and the other substantially midway between the ends of the rods 73a. Similarly, the other end section has two cups 74c for supporting the rods 73c, the endmost cup being relatively long, for a purpose hereinafter described. The central section has three cups 74b, one at each end and one centrally located. Each of the cup members is preferably drawn from sheet metal and has a concentric hexagonal aperture (see Fig. 3) adapted to slidably but non-rotatably receive the shaft 60. The longitudinally extending members or rods are preferably welded to the skirts or flanges of the cups. It is, of course, understood that the 60 number of sections of which the spring arbor is 70 comprised will depend upon the length of the spring employed for lifting a particular door. Where three sections are used, as shown in Fig. 2, the parts are assembled so that the free ends of the rods of the end sections overlap the re- 75

spective ends of the center section; that is to say, the free or right-hand ends of the rods 73a, are placed in alternating relation to the rods 73b and slide over the left-hand end cup 74b of the center section. In like manner, the rods 73c of the other end section are associated with the opposite end of the center section. With this arrangement, the length of the spring arbor may be readily adjusted by sliding the sections on the shafts so as to more or less overlap the rods of the end sections with respect to the center sections. The right-hand end cup 74c of the section 72c is preferably secured against movement longitudinally of the shaft 60 by suitable means, such as the set screw 79.

It will be seen that this spring arbor comprises a relatively light structure supported upon the shaft 60 and substantially filling the interior of the spring 10, the purpose of the arbor being to maintain the spring in cylindrical form as the spring is wound upon the shaft. The interior diameter of the spring has to be materially larger than the diameter of the shaft in order to provide the proper torsional strength for these two elements and, if no provision were made for maintaining the spring in cylindrical form, the pressure of the convolutions of the spring against each other induced by the winding up of the spring would cause the spring to bend or buckle and assume a wavy form, in which condition some of the convolutions would bind upon the shaft 60, thereby causing an uneven distribution of the torsional stresses throughout the length of the spring with the probable consequence that some of the convolutions would be stressed beyond their modulus of elasticity and thereby assume a permanent set. As the spring is wound and unwound, this condition would eventually result in fatigue of the metal of the distorted convolutions and lead to ultimate breakage of the spring. This contingency has been circumvented by the application of the spring arbor described above.

Surrounding the shaft 60 adjacent to the plate 35, I have provided a fixed anchor member or terminal member, generally indicated at 80, which comprises a tube having a flanged end 81 securely riveted to a ratchet wheel 85. This tube overlaps the long cup member 17 of the spring arbor so that the convolution of the spring at the end of the arbor cannot slip down and become wedged between the end of the tube and the shaft 60, and is provided with a pair of oppositely disposed, longitudinal slots 86 and 87 in which are seated a pair of blocks 88 and 89. These blocks are provided with apertures extending in a circumferential direction, as indicated at 90, through which the end of the spring 10 may be threaded, as clearly indicated in Fig. 2. In order to restrain the spring against movement relative to the spring anchor 80, I have provided in each of the blocks 88 and 89 a plurality of radial apertures, as indicated at 91, one aperture 91 being aligned with each of the apertures 90. These apertures 91 are screw threaded and accommodate set screws 92 which bear at their inner ends upon the respective convolutions of the spring 10 to firmly wedge the spring in the blocks. As stated above, the anchor member 80 is rigidly secured at its end adjacent to the plate 35 to a ratchet member, generally indicated at 85, which is in the form of an apertured disk surrounding the shaft 60 and freely rotatable relative thereto. The members 80 and 85 are journaled on a bearing collar

93 which surrounds the shaft 60 and is rigidly secured to the plate 35. The ratchet member 85 is polygonal in shape and has alternate sides thereof bent upwardly in the form of triangular extensions 94, the member illustrated being formed by bending up the corners of a square plate. Each of the extensions 94 is provided with an aperture 95 which extends through the extension and into the disk portion of the ratchet member 85, and the sides of the ratchet member 85 between the extensions are also provided with indentations 97. A ratchet dog 99 is secured to the plate 35 below the member 85 by means of a bolt 100, and is spring pressed by means of a loop spring 102 into engagement in the apertures 95 and indentations 97 to secure the ratchet member 85 against rotation in one direction in any adjusted position. The end of the spring opposite the terminal member 80 is non-rotatably secured to the shaft 60 by means of a rotatable spring anchor, generally indicated at 110. As particularly illustrated in Fig. 4, this spring anchor 110 comprises a pair of plates having their center portions bent so that each fits closely about one-half of the hexagonal shaft 60 to render the member non-rotatable with respect to the shaft. Each plate has radial extensions 112 apertured, as indicated at 114, so that the end of the coiled spring may be threaded therethrough. The free end of the spring is threaded through the apertures 114 and is secured against movement relative to the terminal member by a pair of apertured blocks 115 and 116, similar in all respects to the blocks 88 and 89, clamped on the spring by set screws so as to bear against the radial extensions of the terminal member 110. From the description so far, it will be observed that the spring 10 may be wound up or adjusted by inserting the end of a bar in the apertures 95 and rotating the ratchet member 85, and that the spring will be maintained in its properly tensioned condition by means of the ratchet dog 99 engaging in the apertures or indentations in the ratchet member 85 and by the terminal 110 engaging the end of the spring opposite the end engaged by the terminal member 80. When so tensioned, the spring tends to rotate the shaft 60 in a direction to counterbalance the weight of the door 15. It will also be observed that the length of the tensile portion of the spring may be adjusted to accommodate the spring to different weights of doors and heights of door openings by loosening the set screws 92 and threading the ends of the spring for a greater or lesser extent through the blocks 88 and 89, and 115 and 116. Both the length and the tension of the spring are thus made adjustable to provide for accurate counterbalancing of the door through its entire range of movement and any tendency of the door to stick or jump at either end of its movement may be corrected. As explained above, the spring arbor 72 may be adjusted to follow any change in the length of the spring. The ends of the shaft 60 project beyond the bearings 55 and 55', and have non-rotatably secured thereon cable pulleys 62 and 62'. Cables 64 and 64' extend from the cables 62 and 62', respectively, to the adjacent bottom corners of the door 15. From an inspection of Fig. 2, it will be observed that these cable pulleys are each provided around the external surface thereof with a spiral groove, as indicated at 66, and that the profile of said external surface of each pulley is a parabolic curve. The purpose of such an arrangement is well under-

stood in the art. It is sufficient to say that by this construction the pulleys are effective to compensate the decreasing strength of the spring by applying a decreasing radius during the initial 5 upward movement of the door in which the weight of the door remains constant; and by applying a radius changing within narrower limits during the remaining period of the lift, during which the decrease in the weight of the door substantially 10 compensates the decrease in the strength of the spring.

The lower ends of the cables 64 and 64' are secured to the door by means of a construction particularly illustrated in Figs. 5 and 6, which 15 comprises a combined cable attachment and safety stop. In this construction, a bracket member 117 bent to a generally channel-shaped cross section has one leg thereof secured to the edge of the door, as indicated at 118, and passes around 20 the associated track member 17. The other leg of this bracket member is offset from the edge of the door and has a catch or dog member, generally indicated at 120, pivotally secured thereto by means of a pivot pin or bolt, generally indicated at 25 122. The upper end of the dog member 120 is bent over, as indicated at 124, and apertured, as indicated at 125, to receive the anchor means 127 for the lower end of the cable 64. The lower end of the dog member is directed some- 30 what inwardly towards the frame of the door opening and terminates in a sharp point 130, as particularly illustrated in Fig. 5. The pivot bolt 122 is provided with a reduced portion 131 which extends through a suitable aperture provided in 35 the leg of the bracket member and is screw threaded to receive a nut 132. Washers, as indicated at 133, may be disposed between the nut and the adjacent face of the leg of the bracket member. This bolt is also provided with a somewhat enlarged journal portion 134 separated from the reduced portion 131 by a radial shoulder. This journal portion 134 is adapted to be inserted in a suitable aperture provided in the dog member 120 and by means of which the dog member 40 45 is pivotally secured to the bracket. On the opposite side of the journal portion 134 from the reduced portion 131, the bolt 122 is provided with a still further enlarged portion 135 separated from the journal portion 134 by a radial shoulder. 50 55 This enlarged portion of the bolt is surrounded by a coil spring 136 having its outer end non-rotatably secured to the bolt, as indicated at 137. The opposite end of the spring is provided with an extension 138 secured to the dog member 120 by suitable means, such as a rivet 139. This spring is covered by a cup-shaped cap member 140 provided with a central aperture through which extends a reduced end portion 141 of the bolt 122. This reduced outer end portion is screw 60 threaded and receives a nut 142 which securely clamps the cap member 140 against the radial shoulder separating the enlarged portion 135 of the bolt from the reduced portion 141. From an inspection of Figs. 5 and 6, it will be observed 65 that the action of the spring 136 tends to urge the lower end of the dog member to the left, as viewed in Fig. 5, in which position the sharpened end 130 of the dog member would dig into the jamb of the door opening to prevent the door 70 from being lowered, or from falling. This tendency of the spring is overcome by the tension normally exerted on the cable 64. The operation of these safety catches is such that if the tension on the cables 64 and 64' were released by the 75 failure of any part of the counterbalancing mech-

anism such, for instance, as the breakage of the spring 70, the springs 136 would urge the dog members 120 inwardly so that the points 130 thereof would engage in the jambs of the door opening and stop the door in the position at which the failure of the counterbalancing mechanism occurred and thereby eliminate any danger of injury to the person operating the door. 5

From the above description, it will be observed that I have provided a vertically and horizontally 10 movable overhead door which will be especially smooth and positive in action, which may be easily and accurately counterbalanced by properly tensioning the coil spring 70, and which is rendered safe in use against the failure of any of the 15 counterbalancing parts by the novel safety catches described above.

While I have illustrated and described a particular mechanical embodiment of the idea of my invention, it is to be understood that the invention 20 is not limited thereto and that such changes in the size, shape, and arrangement of parts may be resorted to as come within the scope of the appended claims.

Having now described my invention so that 25 others skilled in the art may clearly understand the same, what I desire to secure by Letters Patent is as follows:

I claim as my invention:

1. In an overhead door construction, a pair of 30 tracks each having a vertical section, a horizontal section, and a curved connecting section; an articulated door comprising a plurality of hingedly connected sections guided by said tracks and movable from a vertical closed position to an 35 overhead and generally horizontal position, an arm pivoted to the rear face of the upper section adjacent each side edge thereof and adapted to support said upper section when the same is in overhead position, rollers carried by the upper 40 free ends of said arms and traveling in the respective tracks, a short channel-shaped track member which is straight throughout the major portion of its length and located above and generally tangential to the curved portion of one of 45 said tracks, tracks at a point between the junctions of said curved portion with the vertical and horizontal track sections, each of said track members having at its lower forward end a cam portion inclined downwardly and forwardly, and a 50 guide member projecting laterally from the side edge of the upper panel adjacent the top edge thereof and adapted to travel in said short track member when the door is raised and lowered, said guide member being adapted to engage said 55 cam portion as the door is brought to final closed position whereby the upper panel is forced towards the door frame.

2. In an overhead door construction, a pair of 60 tracks each having a vertical section, a horizontal section, and a curved connecting section; an articulated door comprising a plurality of hingedly connected sections guided by said tracks and movable from a vertical closed position to an 65 overhead and generally horizontal position, an arm pivoted to the rear face of the upper section adjacent each side edge thereof and adapted to support said upper section when the same is in overhead position, rollers carried by the upper free ends of said arms and traveling in the respective tracks, a short channel-shaped track member which is straight throughout the major portion of its length and located above each curved section and arranged generally tangential thereto at a point intermediate of the 70 75 80 85 90 95 98

length of said curved connecting section, each of said track members terminating at its lower end in a forwardly and downwardly inclined cam portion, each short track member having an upper flange and a lower flange, and studs projecting laterally from the upper door section adjacent the upper edge thereof and adapted to engage in said short track members when the door is raised and lowered, said studs being adapted to engage the upper flanges of said track members upon initial upward movement of the door whereby to swing the upper panel rearwardly, and said studs engaging said cam portions while the door is being brought to final closed position whereby said upper panel is cammed towards the door frame.

3. In a track for overhead doors, a pair of track sections of channel-shape, and means for joining abutting ends of said track sections in aligned relation, said means comprising a bracket plate secured to the end of one of said sections and extending therebeyond, and a hook plate secured to the end of the other section adapted to lie against said bracket plate, said hook plate having a hook along one edge embracing the corresponding edge of said bracket plate.

4. In an overhead door construction, a track having a straight section and a curved section, means for securing the abutting ends of said sections together and to the associated door jamb comprising a plate securing to one of said track sections and extending therebeyond to overlap the other of said track sections, means for securing said plate to said door jamb, a hook plate secured to the other of said track sections and having a bent over edge of hooked shape adapted to receive the corresponding edge of said first plate to align the abutting ends of said track sections with each other, and means for securing said first plate and hook plate together.

5. In an overhead door construction, a vertically movable door, a door jamb, cables for raising and lowering said door and operating means for said cables; a safety catch to restrain said door from falling in the event of failure of said cables or said operating means, said safety catch comprising, a bracket adapted to be secured to the edge of said door adjacent to the bottom thereof, a dog member pivotally secured to said bracket and having a pointed end, a spring acting to urge said pointed end of said dog into engagement with said door jamb, and a connection between said dog member and said cable whereby the tension in said cable overcomes the action of said spring and maintains said dog member clear of said door jamb.

6. In an overhead door construction, a vertically movable door, a door jamb, a track for guiding said door, cables for raising and lowering said door, and operating means for said cables; and a safety catch to restrain said door from falling in the event of failure of said cables or said operating means, said safety catch comprising, a U-shaped bracket having one leg thereof secured to the edge of said door at the bottom thereof, the intermediate portion of said bracket extending around said track to bring the other leg thereof opposite said door jamb, a dog member pivotally secured on said other leg and having a pointed end, a spring acting to urge said pointed end of said dog into engagement with said door jamb, and a connection between said dog and said cable whereby the ten-

sion in said cable overcomes the action of said spring and maintains said dog clear of said door jamb.

7. In an overhead door construction, a pair of tracks each having a vertical section, a horizontal section, and a curved connecting section; an articulated door comprising a plurality of hingedly connected sections guided by said tracks and movable from a vertical closed position to an overhead and generally horizontal position, and means for counterbalancing said door including a rotatable shaft, a torsion spring about said shaft and fixedly anchored at one end and having its other end secured to said shaft so as to rotate therewith, and a skeleton arbor within said spring and of larger diameter than, surrounding, and fixed to, so as to rotate with, said shaft.

8. In an overhead door construction, a pair of tracks each having a vertical section, a horizontal section, and a curved connecting section; an articulated door comprising a plurality of hingedly connected sections guided by said tracks and movable from a vertical closed position to an overhead and generally horizontal position, and means for counterbalancing said door including a rotatable shaft polygonal in cross section, a torsion spring of relatively larger diameter than said shaft and surrounding the same, means for fixedly anchoring one end of the spring, means for securing the other end of the spring to said shaft, and an arbor interposed between said spring and shaft substantially the length of the spring and of smaller diameter than the spring but of relatively larger diameter than the shaft, said arbor having coaxial apertures adapted to slidably and non-rotatably receive said shaft.

9. In an overhead door construction, a pair of tracks each having a vertical section, a horizontal section, and a curved connecting section; an articulated door comprising a plurality of hingedly connected sections guided by said tracks and movable from a vertical closed position to an overhead and generally horizontal position, and means for counterbalancing said door including a rotatable shaft, a torsion spring about said shaft and fixedly anchored at one end and having its other end secured to said shaft so as to rotate therewith, and a skeleton arbor within said spring and of larger diameter than, surrounding, and fixed to, so as to rotate with, said shaft, said spring arbor comprising a plurality of longitudinally adjustable sections having overlapping ends.

10. In an overhead door construction, a pair of tracks each having a vertical section, a horizontal section, and a curved connecting section; an articulated door comprising a plurality of hingedly connected sections guided by said tracks and movable from a vertical closed position to an overhead and generally horizontal position, and means for counterbalancing said door including a rotatable shaft, a torsion spring about said shaft and fixedly anchored at one end and having its other end secured to said shaft so as to rotate therewith, and a skeleton arbor within said spring and of larger diameter than, surrounding, and fixed to, so as to rotate with, said shaft, said arbor comprising a plurality of longitudinally adjustable sections, each section having a plurality of longitudinally spaced apart supporting members and a plurality of longitudinally extending members equally spaced around and secured to said supporting members, the longitudinally extending members at the end of one of said sections being free whereby such ends may overlap the adjacent end of the next section.

11. In an overhead door construction, a pair of tracks each having a vertical section, a horizontal section, and a curved connecting section; an articulated door comprising a plurality of hingedly connected sections guided by said tracks and movable from a vertical closed position to an overhead and generally horizontal position, and means for counterbalancing said door including a rotatable shaft, a torsion spring about said shaft and fixedly anchored at one end and having its other end secured to said shaft so as to rotate therewith, and a skeleton arbor within said spring and of larger diameter than, surrounding, and fixed to, so as to rotate with, said shaft, said arbor comprising a plurality of longitudinally adjustable sections, each section comprising a plurality of spaced apart cups surrounding said shaft and slidable but non-rotatable with respect thereto and a plurality of longitudinally extending rod-like members equally spaced around said shaft and connected to said cups, the rod-like members at the end of one section being free so as to overlap a cup at the end of the adjoining section between the rod-like members of said adjoining section.
12. In an overhead door construction, a pair of tracks each having a vertical section, a horizontal section, and a curved connecting section; an articulated door comprising a plurality of hingedly connected sections guided by said tracks and movable from a vertical closed position to an overhead and generally horizontal position, and means for counterbalancing said door including a shaft parallel to the top edge of said door rotatably mounted in fixed abutments, a coil spring surrounding said shaft between said abutments, means for securing one end of said spring against rotation relative to said shaft, means comprising an anchor member and a ratchet member for restraining the other end of said spring against rotation relative to one of said abutments, said ratchet member comprising a polygonal disk having indentations at the sides thereof and having bent up portions on alternate sides to reinforce the same, a ratchet dog pivoted on said abutment for engaging in said indentations to restrain said ratchet against rotation in one direction relative to said abutment, a cable pulley on each end of said shaft, and a cable operatively connecting each of said cable pulleys to said door.
